UNITED STATES PATENT OFFICE

151,293

DESIGN FOR A DEVICE FOR DISPENSING
LIQUID IN SPRAYED OR GASEOUS FORM

Hamilton R. Stagner, St. Louis, Mo.

Application July 3, 1947, Serial No. 140,088

Term of patent 14 years

(Cl. D62—2)

To all whom it may concern:

Be it known that I, Hamilton R. Stagner, a citizen of the United States, residing at St. Louis, in the city of St. Louis and State of Missouri, have invented a new, original, and ornamental Design for a Device for Dispensing Liquid in Sprayed or Gaseous Form, of which the following is a specification, reference being had to the accompanying drawings forming part thereof.

Fig. 1 is a rear perspective view of a device for dispensing liquid in sprayed or gaseous form showing my new design;

Fig. 2 is a side elevation;

Fig. 3 is a rear elevation;

Fig. 4 is a front elevation; and

Fig. 5 is a bottom plan view of the same.

I claim:

The ornamental design for a device for dispensing liquid in sprayed or gaseous form, as shown.

HAMILTON R. STAGNER.
